CLAIM

The ornamental design for a portable radio speaker
cover or similar article, as shown and described.

DESCRIPTION

FIG. 1 is a front elevational view of a portable radio
speaker cover or similar article showing our new de-
sign;

FIG. 2 is a right side elevational view thereof;

FIG. 3 is a top plan view thereof;

FIG. 4 is a bottom plan view thereof; and,

FIG. 5 is a left side elevational view thereof;

The broken line showing of the portable radio is for
illustrative purposes only and forms no part of the
claimed design.
